UNITED STATES PATENT OFFICE.

EMIL ERNST, OF MAPLEWOOD, MISSOURI, ASSIGNOR TO NORBERT L. LAMM, IRVING W. LONGACRE, AND EMIL ERNST, COMPRISING THE FIRM OF C. P. ROOT BEER COMPANY, OF ST. LOUIS, MISSOURI.

BEVERAGE-DISPENSING APPARATUS.

Application filed October 13, 1924. Serial No. 743,379.

My invention relates generally to beverage dispensing apparatus and, more especially, to a certain new and useful improvement in that class of dispensers wherein it is desirable that the beverage be carbonated or impregnated with air, whereby the liquid may be served with a head or foam.

My present invention has for its chief object the provision of an apparatus of the type stated by which the proportions of so-called "foam" and "solid" of the dispensed fluid or liquid may be regulated and controlled by the operator.

My present invention has for a further object the provision of an apparatus of the type stated which is compact in form and construction, having a greatly reduced number of parts, occupying a much smaller space, and requiring a much smaller investment than heretofore with apparatus of this type.

And with the above and other objects in view, my present invention resides in the novel features of form, construction, arrangement, and combination of parts herein-after described and pointed out in the claim.

In the accompanying drawings,

Figure 1 is a perspective view of a dispensing apparatus embodying my invention;

Figure 2 is a vertical sectional view of the preferred form of dispensing element or member of the apparatus;

Figure 3 is a longitudinal view, mainly in section, of the dispensing-faucet;

Figure 4 is an elevational, so-called functional view of the faucet;

Figure 5 is a cross-sectional view of the faucet;

Figure 6 is a perspective view of a modified form of dispensing apparatus embodying my invention, and

Figures 7 and 8 are cross-sectional views taken approximately on lines 7—7 and 8—8, respectively, Figure 5.

Dispensing apparatus for delivering highly aerated beverages have heretofore, so far as I am aware, consisted of a refrigerating element, a low pressure air tank, a liquid container, and a high pressure air tank. Each of these apparatus also includes suitable piping, cocks, gauges, and connections which require proper and constant adjustments, occupy considerable space, and involve a relatively large investment.

It is desirable in serving highly aerated beverages, such as is popularly known as root beer, that they be served with a head of foam, which is produced by impregnating the liquid at the time it is drawn with either atmospheric or carbonated air. Hence the function of the apparatus is two-fold; namely, it must discharge a measured quantity of so-called "solid" liquid and at the same time must discharge a measured quantity of air or so-called "foam."

The dispensing method heretofore in use consisted of providing a tank of compressed air under low pressure, which was discharged into a cask containing the liquid, thereby forcing the liquid to flow out through the faucet at a higher level. In addition thereto, there was provided a tank containing compressed air at a very much higher pressure, which was, also, caused to be discharged through the same orifice as the liquid and air already mentioned.

It is, therefore, apparent that, as the liquid in the tank decreases and the air pressure from the low pressure tank decreases, the proportions of liquid and air dispensed are subject to wide variation, so that the head or foam varies accordingly.

By my improved apparatus I am enabled to dispense entirely with the low pressure tank and have so combined the operation of the high pressure tank with the dispensing chamber that it automatically maintains a uniform amount of aeration at all times, while at the same time, the character, that is to say, the proportions of so-called "solid" and "foam," of the dispensed liquid are readily controlled and regulated.

Referring now more in detail to the accompanying drawings, 1 designates a suitable cask or cooler, which preferably has a detachable lid 2, and is mounted on a table or other suitable stand 3. Suitable legs 4 are provided to enable a connecting-pipe 15 to enter the bottom of the cask or other container 1. The other end 5 of the pipe 15 is connected to a hermetically sealed tank 6, which is provided with suitable needle-valves 7 and 7^a to regulate the flow of the gases and liquids contained in the tank 6. The tank 6 contains a predetermined amount of liquid and is then subjected to an air pressure by any suitable outside means. Within the cask 1, a supply-chamber 8 is

provided and so positioned that broken ice or other refrigerating substance 9, may be packed around it, the chamber or receptacle 8 being suitably supported in position, as 5 by means of the connecting pipes, as shown. The supply tank 8 is provided with a float 10, centrally positioned therein and adapted to rise and fall with the level of the liquid contained in the supply tank 8. A valve- 10 stem 11, is connected at the center of the float 10 and extends upwardly through an opening 12 in the top of the supply-chamber 8 sufficiently large to vent the tank when the air-valve is off its seat. Adjacent the 15 end of the valve stem 11 is a valve seat 13. A conventional pressure reducing and regulating valve 14 is mounted upon the supply pipe 15, which leads at its upper end into the supply-chamber 8 and at its lower end 20 communicates with the pressure-tank 6.

Suitably mounted upon the cask 1, as best seen in Figure 2, is a faucet 18, which comprises a body 19, rigidly fitting in recesses in which are non-rotatable, preferably hexagonal washers 20 and 20^a. Through the washers 20, 20^a, are perforations or orifices 21, 21^a respectively, in constant open communication with ducts 22, 22^a, respectively, in the faucet-body 19. Leading from the 25 faucet-body 19 into a nozzle 23, are outlet-passages or ducts 24 and 24^a, one of which, namely, the duct 24, being preferably of larger diameter than the other. Mounted for rotatory movement upon the faucet-body 30 19, are members 25 and 25^a formed with U-shaped orifices 26, 26^a, respectively. Tension-screws 27 and 27^a are provided to hold the rotatable members 25 and 25^a in unbreakable contact with the washers 20 and 20^a, and 35 also for the purpose of adjusting against wear of the contacting members 20 and 25 and 20^a and 25^a. The rotatable members 25 and 25^a are caused to rotate by means of a lever or handle 28, the outer end of which 40 is preferably spherical, but may be made in any ornamental design, the opposite end being forked and adapted to straddle the body 19 of the faucet and having the terminals of its forks rigidly fixed to the rotatable members 25 and 25^a.

Leading from, and in open communication at one end with, the supply-pipe 15 intermediate its ends, as at 16, is a branch pipe 17, preferably coiled for cooling purposes within the cask 1 and which, at its other end, is in communication with the duct 22, and, as best seen in Figure 3, a suitable needle- and air-valve 29 is provided upon the faucet to regulate the flow of liquid from the supply- 55 tank 6 through the faucet-duct 22.

Leading from the tank or chamber 8 to the other duct 22^a, is a liquid supply-pipe 30.

Normally, as when the lever or handle 28 is in a vertical position or in the position 60 shown in full lines in Figure 4, the parts

are so constructed that both faucet-outlets 24, 24^a, are entirely closed. When the handle 28 is partly swung forwardly or into, for instance, the dotted position indicated at A, Figure 4, the orifice 21^a in the washer 20^a 70 and the U-shaped orifice 26^a in the rotatable member 25^a are first caused to register, permitting the flow of the so-called "solid" liquid from the supply-tank 8 through the outlet 24^a of the faucet 18. When the handle 28 is further swung forwardly or into the dotted position indicated at B, Figure 4, the orifices 21^a and 26^a continue in registration and the U-shaped orifice 26 in the rotatable member 25 is also brought into registration 80 with the orifice 21 of washer 20, when both the air and liquid under high pressure from the tank 6 is permitted to flow through the faucet-outlet 24 simultaneously with the so-called "solid" fluid. Thus, the one outlet 85 opening in advance of and conversely closing behind the other, the operator is enabled to readily control the character, that is to say, the "solid" and "foam" parts, of the dispensed beverage. 90

The pressure-regulating valve 14 is interposed in the pipe-line 15 between the tank 6 and the supply-chamber 8. This valve may be of any conventional type, and its purpose is to reduce the pressure in the fluid flowing from tank 6 into tank 8 to a point or amount that but a small quantity of air will escape into the supply chamber 8 and out through the air-valve 12. The liquid carried along with the air through pipe 15 100 will discharge into the supply tank 8 until the level rises sufficiently high to cause the float 10 to close the air valve. When the quantity of air or pressure within the supply tank 8 rises to a point where neither air 105 nor liquid will flow into the supply chamber, the flow from tank 6 into tank 8 ceases, until the float 10 has again lowered as the supply is drawn from the tank 8 by means of the faucet 18, when the same cycle of operation will again be repeated. Thus a constant air pressure and a constant liquid level 110 are maintained in the supply tank 8, so that substantially uniform amount of aeration takes place each time the faucet is operated. 115

The tank 6 is made of suitable material to cause it to withstand relatively high hydraulic and pneumatic pressures and is hermetically sealed by means of a conventional type ejector provided with the regulating needle valves 7 and 7^a for adjusting the amount of air and liquid to be discharged through the single discharge 15.

A conventional pressure gauge 31 indicates the pressure at which air and liquid is flowing into the supply chamber 8. 125

A modified form of my invention is shown in Figure 6, where, instead of placing the pressure-gauge and pressure-reducing valve within the container 1, both are disposed be- 130

neath and on the outside of the container 1, as shown. A cut-off valve 32 may be used to prevent the flow of liquid and air from the tank 6 when adjusting the pressure 5 valve 14.

I am aware that changes in the form, construction, arrangement, and combination of the several parts of my new dispensing apparatus may be made and substituted for those herein shown described without departing from the nature and principle of my invention.

Having thus fully described my invention, what I claim and desire to secure by 15 Letters Patent is:

In a beverage dispensing apparatus, a faucet including a body-member, first and second inlet ports leading into the body-member, a discharge-nozzle, first and second 20 outlet ports separately leading from the body-member into the nozzle, and means for

successively establishing communication between the first inlet and outlet ports and between the second inlet and outlet ports, respectively, the first pair in advance of the other, then maintaining communication simultaneously between the respective pairs of ports, and then successively breaking communication between the respective pairs of ports, the second pair in advance of the first, 25 whereby fluid entering the first inlet port is first admitted to the discharge-nozzle and the last to be cut off, said means comprising a pair of separate orificed valve-members mounted for rotatory movement in the body-member, and a single oscillatory lever for rotatorily actuating both said valve-members.

In testimony whereof, I have signed my name to this specification.

EMIL ERNST.
